Filed Jan. 7, 1958, Ser. No. 707,603

12 Claims. (Cl. 317—147)

This invention relates to apparatus for remotely controlling the operation of a distant mechanism. More particularly, the invention relates to apparatus for transmitting signals in a particular code from an automobile toward a garage and for receiving the signals at the garage to control the opening and closing of a door in the garage.

In this advancing age of automation, equipment is constantly being invented and developed to simplify the tasks of men and women. For example, apparatus is now being used to transmit signals from an automobile as the automobile approaches a garage so that the garage door can be opened without any necessity for the driver to get out of the car. Similarly, the apparatus can be operated to close a garage door after the automobile has left the garage. This apparatus has been especially desirable in inclement or cold weather and has been particularly useful to women drivers at night.

Remote control equipment for operating garage doors has been steadily increasing in popularity. This increase in popularity has presented certain problems. One problem has resulted from the fact that all of the manufacturers are allowed only a few transmitting frequencies by governmental authorities such as the Federal Communications Commission. When a number of different installations are made by different manufacturers in a particular area, it may sometimes occur that a car approaching a particular garage may open the door for that garage as well as the door for other garages near the particular garage. This may result from the fact that the particular garage may have an installation of one manufacturer, while other garages in the area may have an installation of other manufacturers. For this reason, it has become necessary to differentiate between installations in a neighborhood even though such differentiation has been made difficult by the use of a single carrier frequency for the transmitted signals.

Various attempts have been made to encode the carrier signals with individual and particular patterns to distinguish each installation from the others. These attempts have not been entirely successful from an operational standpoint since each garage installation has not been entirely independent in operation from all of the other garage installations in the neighborhood. Furthermore, the equipment resulting from such attempts has been expensive in spite of the incomplete success from an operational standpoint. This invention provides a system for overcoming the above disadvantages and at the same time providing equipment of reduced cost.

The system constituting this invention produces a carrier signal of the frequency specified by the governmental authorities. This carrier signal is alternately modulated on a time-sharing basis by signals of a relatively low frequency and second signals of a relatively high frequency. Each of the low frequencies and high frequencies can be adjusted for different installations to provide a differentiation between the installations.

For example, one installation may use signals of 9 kilocycles per second to constitute the low frequency and signals of 29 kilocycles per second to constitute the high frequency. Another installation may respectively use signals of 11.5 and 34 kilocycles per second as the low and high frequencies. Similarly, a third installation may

2

use modulating signals of 9 and 34 kilocycles per second on a time-sharing basis. By using circuits tuned to the particular frequencies, each installation is able to pass only signals at the particular frequencies selected for that installation. The system is so designed that the garage door can be opened only when the modulating signals at both the low and high frequencies are able to pass the tuned circuits at the installation.

The system constituting this invention utilizes novel techniques to simplify the construction of the system. For example, substantially the same circuitry is used at the transmitter of an automobile to produce the modulating signals of relatively low frequency and the modulating signals of relatively high frequency on a time-sharing basis. At the receiver, novel circuitry is used to actuate the garage door mechanism only when both modulating signals of the selected values at the low and high frequencies are received concurrently.

Another advantage of the apparatus constituting this invention results from the use of the antenna normally provided on an automobile to receive radio signals as the antenna of transmitting signals to the receiver at the garage door. This is accomplished by short-circuiting the input to the radio at the time that signals are to be transmitted to the receiver at the garage door. By short-circuiting the input to the radio, the impedance of the radio cannot be coupled to the antenna to affect the tuning of the transmitted signals. Furthermore, the radio cannot be damaged in any way in case of any considerable intensity in the transmitted signals.

The apparatus constituting this invention also has certain other advantages. It utilizes a simple mechanism to attach the transmitter under the dashboard of an automobile. This attachment is made in such a way that the transmitter can be easily attached to the dashboard by fastening one screw and can be easily detached from the dashboard at any time by unfastening the screw.

In the drawings:

FIG. 1 is a diagram of electrical circuitry showing the electrical construction of a transmitter included in one embodiment of the invention;

FIG. 2 is a diagram of electrical circuitry showing the electrical construction of a receiver included with the transmitter shown in FIG. 1 in one embodiment of the invention;

FIG. 3 is a fragmentary perspective view of the housing for the transmitter shown in FIG. 1 and illustrates the manner in which the transmitter housing may be disposed under the dashboard of an automobile;

FIG. 4 is an exploded perspective view of the different members forming the transmitter housing shown in FIG. 3 and illustrates how the various members may be connected to one another and to the automobile dashboard;

FIG. 5 is a fragmentary sectional view illustrating the construction and relative disposition of a push button shown in FIG. 4 and of members associated with the push button including a pair of switches included in the circuit diagram shown in FIG. 1;

FIG. 6 is a chart illustrating possible values for modulating signals of low and high frequencies produced on a time-sharing basis by the transmitter shown in FIG. 1;

FIG. 7 is a chart illustrating the possible combinations of modulating signals at the low and high frequencies and further illustrating the value of the capacitance which has to be added to obtain the desired combination of modulating frequencies; and

FIG. 8 is a schematic diagram illustrating the different possible connections between pairs of terminals in a connector board shown in FIG. 1 to obtain the production of modulating signals at either high or low frequencies or the production of modulating signals at both high and low frequencies on a time-sharing basis.

In the transmitter shown in FIG. 1, an antenna 10 is mounted in any suitable and convenient manner on an automobile to send signals toward a garage door. The antenna 10 may be similar to those used on automobiles at present to receive signals for operating the radios in the automobiles. The antenna 10 may be used to receive signals for introduction to the car radio during the time that it is not being used to obtain the opening or closing of a garage door. The connection from the antenna 10 through a coil 11 to the input to a radio (not shown) in an automobile is indicated schematically by a cable 12.

A pair of ganged single-pole single-throw switches 14 and 16 are included in the transmitter circuitry shown in FIG. 1. The stationary contact of the switch 14 is connected to the common terminal between the coil 11 and the cable 12 and the movable contact of the switch 14 is grounded. The movable contact of the switch 16 is also grounded and the stationary contact of the switch is connected to the movable contact of an electromagnetically driven vibrator 18. The vibrator 18 may be of any suitable construction such as a type 1601 manufactured by the P. R. Mallory Company. The vibrator 18 is provided with two stationary contacts which will hereafter be designated as the upper and lower stationary contacts to conform with the relative positioning of these contacts in FIG. 1. The movable contact of the vibrator 18 may be spring loaded for normal disposition against the lower stationary contact of the vibrator in FIG. 1.

The upper stationary contact of the vibrator 18 is connected to one terminal of an energizing coil 20 included in the vibrator and the other terminal of the coil 20 is connected to the movable contact of the vibrator. The upper stationary contact of the vibrator 18 also has a common connection with one terminal of the primary winding in a transformer generally indicated at 22. The other terminal of the primary winding in the transformer 22 is connected to the middle one of three terminals in an adaptable terminal board generally indicated at 24.

A resistance 26 having a suitable value such as approximately 3 ohms is connected between the left and middle terminals of the board 24 and a resistance 28 having a suitable value such as approximately 13 ohms is connected between the left and right terminals of the board 24. The left terminal of the board 24 is connected to one terminal of a battery 25 in an automobile, the other terminal of the battery being grounded. Although the left terminal of the board 24 is shown as being connected to the positive terminal of the battery 25 in FIG. 1, it can also be connected as effectively to the negative terminal of the battery. The right terminal of the board 24 is connected to first terminals of the filaments in the vacuum tubes used in the transmitter, the second terminals of the filaments being grounded. Actually, in the embodiment of the transmitter shown in FIG. 1, only two tubes are included and both of these tubes may be disposed within a single envelope.

The terminal board 24 and the resistances 26 and 28 are included to adapt the transmitter shown in FIG. 1 for operation in automobiles using 6-volt batteries and in automobiles using 12-volt batteries since the new automobiles are now using 12-volt batteries whereas the old automobiles have been using 6-volt batteries. When the transmitter shown in FIG. 1 is to be energized from a 12-volt battery, the connections are made as shown in FIG. 1 and as described above. For operation of the transmitter shown in FIG. 1 from a 6-volt battery, the three terminals in the board 24 are short-circuited to one another.

A rectifying stage generally indicated at 32 is connected across the secondary winding of the transformer 22. The rectifying stage 32 includes a capacitance 34 which is in parallel with the secondary winding of the transformer 22 and which is provided with a suitable value such as approximately 0.01 microfarad. One terminal of the capacitance 34 is grounded and the other

terminal of the capacitance is connected to the plate of a diode 36, which may be a type HW 125-75, manufactured by the Siemens Company of Germany. The cathode of the diode 36 has a common connection with the first terminal of a capacitance 38, the second terminal of which is grounded. The capacitance 38 may have a suitable value such as approximately 4 microfarads.

The voltage on the cathode of the diode 36 is applied to an intermediate tap in a coil 40. The coil 40 is magnetically coupled to the coil 11 to induce signals in the coil for introduction to the antenna 10. A capacitance 42 having a suitable value such as approximately 10 micromicrofarads is in parallel with the coil 40 to tune the coil to a particular carrier frequency. The lower terminal of the capacitance 42 in FIG. 1 is connected to a first terminal in a crystal 44 which may be constructed to provide a suitable carrier frequency such as approximately 27.12 megacycles. This frequency is assigned by the Federal Communications Commission. The frequency is the same for all manufacturers regardless of the number of manufacturers and regardless of the number of sets.

The other terminal of the crystal 44 is connected to the control grid of a tube 46. The tube 46 may be included with another tube in a single envelope designated as a type 6AN8. When two tubes are included in a single envelope, only one envelope is required in the transmitter, as will be seen from the subsequent discussion.

A capacitance 45 is connected between the control grid of the tube 46 and ground to neutralize any capacitive effects in the crystal 44. The capacitance 45 may be provided with a suitable value such as approximately 10 micromicrofarads. The control grid of the tube 46 is biased by a pair of resistances 48 and 50 connected in series between the control grid and ground. The resistances 48 and 50 are respectively provided with suitable values such as approximately 10 kilo-ohms and 22 kilo-ohms.

The plate of the tube 46 is connected to the upper terminals of the coil 40 and the capacitance 42 in FIG. 1. The cathode and suppressor grids of the tube 46 are grounded. The screen grid is positively biased from the cathode of the diode 36 through a network formed by a pair of resistances 52 and 55, which are respectively provided with suitable values such as approximately 56 kilo-ohms and 3.3 kilo-ohms. A capacitance 54 having a suitable value such as approximately 0.001 microfarad is connected between the screen grid of the tube 46 and ground.

Signals are applied to the common terminal between the resistances 48 and 50 through a suitable coupling capacitance 58 from the plate of a tube 60 which may be included in a common envelope with the tube 46. The plate of the tube 60 is adapted to receive a positive potential through a suitable resistance 56 from the cathode of the diode 36. The resistance 56 and the coupling capacitance 58 may respectively have suitable values such as approximately 6.8 kilo-ohms and 0.001 microfarad. The cathode of the tube 60 has a common connection with one terminal of a resistance 62, the other terminal of which is grounded. The resistance 62 may have a suitable value such as approximately 2.2 kilo-ohms. The cathode of the tube 60 also has a common terminal with an intermediate tap on a tuning coil 64.

A resistance 66 having a suitable value such as approximately 10 kilo-ohms extends electrically between the grid of the tube 60 and ground. A capacitance 68 is connected between the grid of the tube 60 and one end terminal of the tuning coil 64, the other end terminal of the tuning coil being grounded. A capacitance 70 having a suitable value such as approximately 220 micromicrofarads is in parallel with the tuning coil 64.

A capacitance 72 and an adjustable tuning capacitance 76 have first terminals connected to the ungrounded end terminal of the tuning coil 64 and have second terminals

connected to an intermediate terminal in a connector board 74. The combined value of the capacitances 72 and 76 is dependent upon the frequencies to be provided for modulating signals of relatively low frequency. The combined value of the capacitances 72 and 76 for different combinations of low and high frequencies may be seen from a chart shown in FIG. 7. Variations in the combined value may be obtained by adjusting the capacitance 76 or by varying the value of the capacitance 72.

The connector board 74 is provided with left, intermediate and right terminals, and the left terminal is grounded. To obtain only modulating signals of relatively high frequency, none of the terminals in the connector board 74 is connected to any of the other terminals in the board. This may be seen from the schematic diagram shown in FIG. 8. The left and intermediate terminals in the connector board are connected together to obtain only modulating signals of relatively low frequency. For the production of modulating signals of both low and high frequencies, the intermediate and right terminals in the board 74 are connected together. The different electrical arrangements between the terminals in the board 74 are illustrated in FIG. 8. The different circuit arrangements produced by such connections will be described in detail subsequently.

The receiver shown in FIG. 2 is located at the garage door and is designed to receive signals for opening or closing the door. The receiver includes an antenna 100 connected in a series circuit to ground with a coil 102. A coil 104 is magnetically coupled to the coil 102 and is in parallel with a capacitance 106 having a suitable value such as approximately 10 micromicrofarads. First terminals of the coil 104 and the capacitance 106 are grounded. A capacitance 108 and a resistance 110 are in series across the coil 104 and the capacitance 106. The capacitance 108 and the resistance 110 may be respectively provided with suitable values such as approximately 100 micromicrofarads and 4.7 kilo-ohms.

The common terminal between the capacitance 108 and the resistance 110 is connected to the control grid of a tube 112, the cathode and suppressor grid of which are grounded. The tube 112 may be included with another tube in an envelope designated as a type 6X8. A capacitance 114 having a suitable value such as approximately .01 microfarad is connected between the screen grid of the tube 112 and the ground. A resistance 116 is connected between the screen grid of the tube 112 and a source 123 of direct voltage to apply a limited potential of positive polarity to the screen grid. A capacitance 118 is connected between the resistance 116 and ground to decouple the positive potential from the source 123 relative to ground. The resistance 116 may have a suitable value such as approximately 56 kilo-ohms and the capacitance 118 may have a suitable value such as approximately 0.01 microfarad.

A tuned circuit is connected to the plate of the tube 112. The tuned circuit includes a capacitance 120 having a suitable value such as approximately 10 micromicrofarads and also includes the primary winding of a transformer 122. Second terminals of the capacitance 120 and the primary winding of the transformer 122 are connected to the positive terminal of a source 123 of direct voltage to receive a suitable potential such as approximately +140 volts.

The secondary winding of the transformer 122 has one terminal grounded and has the other terminal connected to the cathode of a diode 124, which may be a type 1N82A. The plate of the diode 124 has a common terminal with the ungrounded terminal of a resistance 126 and with one terminal of a capacitance 128. The resistance 126 and the capacitance 128 may be respectively provided with suitable values such as approximately 100 kilo-ohms and 470 micromicrofarads.

The second terminal of the capacitance 128 is connected to the ungrounded terminal of a resistance 130 having

a suitable value such as approximately 10 megohms and is also connected to the grid of a tube 132 which may be included in the same envelope as the tube 112. The cathode of the tube 132 is grounded and the plate of the tube is adapted to receive a positive potential. This potential is applied from the same terminal of the voltage source 123 as the tuned circuit formed by the capacitance 120 and the primary winding of the transformer 122. This potential is applied to the plate of the tube 132 through a resistance 134 having a suitable value such as approximately 47 kilo-ohms.

A capacitance 136 is disposed electrically between the plate of the tube 132 and ground. A capacitance 138 and a resistance 140 are in series across the capacitance 136. The capacitance 138 and the resistance 140 may be provided with suitable values such as approximately 0.01 microfarad and approximately 1 megohm. The common terminal between the capacitance 138 and the resistance 140 is connected to the control grid of a tube 142 which may be included with another tube in an envelope designated as type 12AT7. The cathode of the tube 142 is grounded.

The plate of the tube 142 is adapted to receive a positive potential from the same terminal of the voltage source 123 as the plate of the tube 132. This potential is applied to the plate of the tube 142 through a resistance 144 having a suitable value such as approximately 47 kilo-ohms. A coupling capacitance 146 and a resistance 148 are in series between the plate of the tube 142 and ground. The capacitance 146 and the resistance 148 may be respectively provided with suitable values such as 0.001 microfarad and 470 kilo-ohms. The common terminal between the capacitance 146 and the resistance 148 is connected to the control grid of a tube 150 having its cathode grounded. The tube 150 may be included in the same envelope as the tube 142.

The same positive potential is applied to the plate of the tube 150 as is applied to the plates of the tubes 132 and 142. This potential is applied through a resistance 152 having a suitable value such as approximately 47 kilo-ohms. One terminal of a coupling capacitance 154 having a suitable value such as approximately 0.01 microfarad is also connected to the plate of the tube 150. The other terminal of the capacitance 154 is connected to the plate of a diode 156 and to the cathode of a diode 160. The diodes 156 and 160 may be included in a type IRC 9KR22 manufactured by the International Resistance Company. The cathode of the diode 156 is grounded and the plate of the diode 160 is biased at a suitable potential such as approximately -2 volts from the voltage source 123. A capacitance 162 having a suitable value such as approximately 0.01 microfarad extends electrically from the plate of the diode 160 to ground.

The second terminal of the capacitance 154 also has common connections with first terminals of capacitances 166 and 168. A tuned circuit formed by an adjustable coil 170 and a capacitance 172 in parallel is connected between the second terminal of the capacitance 166 and ground. Similarly, a tuned circuit formed by an adjustable coil 174 and a capacitance 176 in parallel is connected between the second terminal of the capacitance 168 and ground. The second terminals of the capacitances 166 and 168 are also respectively connected to first terminals of capacitances 180 and 182, each of which is provided with a suitable value such as approximately 0.001 microfarad.

Second terminals of the capacitances 180 and 182 are connected to the control grids of tubes 184 and 186 which may be included in a single envelope designated as a type 6CG7. The cathodes of the tubes 184 and 186 are grounded and the plates of the tubes are coupled electrically to each other through a pair of resistances 188 and 190 in series. Each of the resistances 188 and 190 is provided with a suitable value such as approximately 33 kilo-ohms. The plates of the tubes 184 and 186 are

also respectively connected to first terminals of a pair of capacitances 192 and 194, each having a suitable value such as approximately 0.001 microfarad.

The second terminal of the capacitance 192 has a common connection with the cathode of a diode 196, the plate of which is connected to the voltage source 123 to receive a suitable negative potential such as approximately -7.5 volts. Resistances 198, 200 and 202 are in series between the control grid of the tube 184 and the plate of the diode 196. The resistances 198, 200 and 202 may be respectively provided with suitable values such as 470 kilo-ohms, 100 kilo-ohms and 2.2 megohms. The common terminal between the resistances 200 and 202 is also connected to the second terminal of the capacitance 192. A capacitance 204 having a suitable value such as 0.01 microfarad is connected between the plate of the diode 196 and the common terminal between the resistances 198 and 200.

Similarly, the second terminal of the capacitance 194 is connected to the cathode of a diode 206, the plate of which is adapted to receive the negative potential of approximately -7.5 volts from the voltage source 123. Resistances 208, 210 and 212 are in series between the control grid of the tube 186 and the plate of the diode 206. The resistances 208, 210 and 212 may be provided with values respectively corresponding to those of the resistances 198, 200 and 202. The common terminal between the resistances 210 and 212 is connected to the second terminal of the capacitance 194. A capacitance 214 having a suitable value such as 0.01 microfarad is connected between the plate of the diode 206 and the common terminal between the resistances 208 and 210.

A relay coil 218 and a resistance 220 extend electrically in series from the common terminal between the resistances 188 and 190 to the terminal in the voltage source 123 for applying the positive potential of approximately +140 volts. The resistance 220 may be provided with a suitable value such as approximately 1.5 kilo-ohms. A capacitance 222 having a suitable value such as approximately 50 microfarads is in parallel with the series branch formed by the relay 218 and the resistance 220.

A switch 224 is magnetically coupled to the coil 218. The switch 224 may be included in apparatus for obtaining the operation of a garage door to either an opened position or a closed position. For example, the switch may be included in apparatus disclosed and claimed in U.S. Patent 2,805,059, issued September 13, 1957, to Willard J. Green. This apparatus is illustrated schematically at 226 in FIG. 2. The apparatus may include a motor which is connected in a circuit with the switch 224 to become energized upon the closure of the switch.

In order to set the transmitter shown in FIG. 1 into operation, the ganged switches 14 and 16 are manually closed. When the switch 14 is closed, it grounds the coil 11 and the ungrounded terminal of the cable 12 to prevent radio signals received by the antenna 10 from being introduced to the radio (not shown) in an automobile. This mutes the automobile radio so that power from the transmitter shown in FIG. 1 cannot be introduced to the radio. This is desirable to prevent the automobile radio from being damaged, especially when the power output from the tube 46 is not limited in a manner which will be described in detail subsequently. Furthermore, by grounding the input to the automobile radio, the radio cannot introduce any reactance to the antenna 10 and the coil 11 to affect the operation of the antenna and change the frequency of response of the coil.

The switch 16 becomes closed at the same time as the switch 14. This grounds the movable contact of the vibrator 18. Since the movable contact of the vibrator 18 normally engages the lower stationary contact in FIG. 1, a continuous circuit is established which includes the automobile battery 25, the primary winding of the transformer 22, the coil 20 and the stationary and movable contacts of the switch 16. This current causes the coil

20 to become energized so as to actuate the movable contact of the vibrator 18 into engagement with the upper stationary contact of the vibrator. In this position of the movable contact of the vibrator 18, the coil 20 becomes short-circuited. This causes the movable contact of the vibrator to return to a position engaging the lower stationary contact of the vibrator. In this way, the movable contact of the vibrator 18 alternates in engaging the upper and lower stationary contacts of the vibrator at a frequency dependent upon the characteristics of the spring loading of the movable contact.

Current flows through the primary winding of the transformer 22 whether the movable contact of the vibrator 18 is engaging the upper or lower stationary contacts of the vibrator. However, in the lower position of the movable contact in the vibrator 18, the coil 20 is included in a series circuit with the primary winding of the transformer 22, whereas in the upper position of the movable contact, the coil 20 is shorted out of the circuit. This produces variations in the current flowing through the primary winding of the transformer 22.

The current flowing through the primary winding of the transformer 22 passes directly between the left and intermediate terminals of the connector board 24 in FIG. 1 when the automobile battery is adapted to supply 6 volts. For the cars employing 12-volt batteries, the current passes through the resistance 26 between the left and intermediate terminals of the connector board 24. In this way, the system constituting this invention is easily adapted for use with both types of automobile batteries included at present in automobiles.

The variations in the current flowing through the primary winding of the transformer 22 during alternate half cycles in the operation of the vibrator 18 cause a voltage to be induced in the secondary winding of the transformer 22. The voltage induced in the secondary winding has an increased amplitude relative to the voltage induced in the primary because of the turns ratios in the windings. The increased voltage in the secondary winding of the transformer 22 is rectified by the stage formed by the capacitances 34 and 38 and the diode 36. The voltage is introduced through suitable resistances to the screen grid of the tube 46 and the plate of the tube 60 and is also introduced through the coil 40 to the plate 45 of the tube 46.

When a positive potential is introduced to the plate of the tube 60, current flows through the tube and the tuning coil 64. The coil 64 and the capacitance 70 provide a tuning circuit resonant at a relatively high frequency constituting a first modulating frequency. This frequency is selected on an individual basis for different installations and is variable in accordance with adjustments made in the tuning coil 64. As may be seen in the chart shown in FIG. 6, at least seven different modulating frequencies of relatively high value may be provided by adjusting the tuning coil 64. These frequencies may be selected in a range between 29 kilocycles per second and 52 kilocycles per second. It should be appreciated that both the range of the modulating signals at the high frequencies and the number of choices in this range may be considered as arbitrary and that a different range and a different number of choices in the range may conveniently be chosen.

During alternate half cycles in the operation of the vibrator 18, the movable contact of the vibrator engages the lower stationary contact in FIG. 1. This causes a ground to be applied to the capacitances 72 and 76 through a circuit including the movable and stationary contacts of the switch 16, the movable and lower stationary contacts of the vibrator 18, and the right and intermediate terminals in the connector board 74. This circuit is established only during the time that the right and intermediate terminals in the connector board 74 are bridged by a lead to produce the operation designated 75 as "high and low frequencies" in FIG. 8. By grounding

the capacitances 72 and 76 in alternate half cycles, the capacitances 72 and 76 are placed in parallel with the capacitance 70 to vary the resonant frequency of the tuning circuit formed by the capacitances and the tuning coil 64.

The introduction of the capacitances 72 and 76 to the tuned circuit formed by the coil 64 and the capacitance 70 causes the resonant frequency of the tuned circuit to decrease. The amount of the decrease in the resonant frequency is dependent upon the values of the capacitances 72 and 76 and can be varied by adjusting the value of the capacitance 76. By proper adjustments in this value, the resonant frequency can be varied in increments between a suitable range such as 9 kilocycles per second and 35.5 kilocycles per second. For example, at least nine increments in range such as shown in FIGS. 6 and 7 can be obtained by proper adjustments in the value of the capacitance 76. It should be appreciated that this range and the number of choices in the range can also be considered as arbitrary and, therefore, can be amended without affecting the scope of the invention.

It will thus be seen that modulating signals of first and second frequencies are produced in the tube 60 on a time-sharing basis. In alternate half cycles of the vibrator 18, signals of relatively high modulating frequency are produced, and in the other half cycles signals of a relatively low modulating frequency are produced. A considerable number of different combinations of relatively high and low modulating frequencies can be obtained by adjusting the tuning coil 64 and the capacitance 76.

As will be seen from the subsequent discussion, each installation at a garage is provided with a different combination of low and high modulating frequencies to distinguish the installation from all other installations in the neighborhood. A garage door can be operated only when the receiver at the door receives carrier signals modulated with both low and high modulating frequencies of selected values. It should be appreciated that the ranges of the low and high modulating frequencies tend to overlap somewhat. However, combinations should be provided only where the high modulating frequency exceeds the low modulating frequency. This tends to restrict somewhat the number of combinations between the low and high modulating frequency, but a sufficient number of combinations are still available to provide a distinction between different installations in a neighborhood.

A possible number of different combinations of low and high modulating frequencies may be seen from the chart shown in FIG. 7. As will be seen, the combinations not considered desirable are indicated by an "X" in the chart shown in FIG. 7. Nineteen possible combinations are designated by an "X" out of a total of 63 such possibilities so as to leave 44 actual possibilities. The chart shown in FIG. 7 also indicates the value of the capacitance 72 which has to be added in microfarads in order to obtain the selected frequency in the low modulating range. As will be seen, the capacitance 72 would not have to be included for at least some of the actual combinations available. It should be appreciated that the inclusion of the capacitance 72 only produces a rough approximation of the desired frequency and that fine variations may have to be made by adjusting the capacitance 76 in order to obtain the desired frequency.

FIG. 8 illustrates the possible connections between the different terminals in the connector board 24. For the production of both low and high frequencies on a time-sharing basis as set forth above, the intermediate and right terminals are connected together. When modulating signals at only the low frequency are desired, the left and intermediate terminals are connected together. This causes a ground to be constantly established to the capacitances 72 and 76 regardless of the positioning of the movable contact in the vibrator 18 such that the capacitances are always included in the tuned circuit.

For the production of modulating signals at only the

high frequencies, no connections are made between the different terminals in the connector board 24. This prevents the capacitances 72 and 76 from being grounded regardless of the positioning of the movable contact of the vibrator 18. Since the capacitances 72 and 76 are never grounded, the tuned circuit is constantly formed only by the coil 64 and the capacitance 70 to provide modulating signals at the high frequencies.

The connections to the terminal board 74 for obtaining either signals of low modulating frequency or signals of high modulating frequency are provided for certain reasons. For example, an important reason is to facilitate the alignment of the receiver and the transmitter to the selected modulating frequencies so that the receiver will respond properly to the transmitted signals. By testing for each modulating frequency separately, problems resulting from the production of harmonic signals are considerably reduced.

The modulating signals produced on the plate of the tube 60 are introduced to the control grid of the tube 46 through the coupling capacitance 58 and the resistance 48. The tube 46 is included in a modified Colpitts type of oscillator. The oscillator also includes the crystal 44 and the resonant circuit formed by the coil 40 and the capacitance 42. This resonant circuit is tuned to substantially the same frequency as the resonant frequency of the crystal 44. This frequency may have a suitable value such as approximately 27.12 megacycles. However, it will be appreciated that any other suitable carrier frequency can also be used. The frequency of the carrier signals produced by the modified Colpitts oscillator is designated for all manufacturers by the Federal Communications Commission. Since all manufacturers are assigned the same carrier frequencies, it is important that a garage installation of one manufacturer should not be affected by signals from transmitters installed in automobiles by other manufacturers.

The power output represented by the carrier signals from the tube 46 is limited in accordance with the requirements of the Federal Communications Commission. This power input is designated as 100 milliwatts maximum to the tube 46. The power limitation is obtained by limiting the potential on the screen grid of the tube 46 to that approaching ground. The potential on the screen grid of the tube 46 is controlled by the action of the network formed by the resistances 55 and 52. However, it should be appreciated that an increased potential can be applied to the screen grid of the tube 46 if no power limitations are imposed on the transmitter by governmental authorities.

The carrier signals produced by the modified Colpitts oscillator are modulated on a time-sharing basis with the signals of low and high frequencies produced on the plate of the tube 60. These signals are induced from the coil 40 to the coil 11 so that they can be transmitted by the antenna 10 to the antenna 100 (FIG. 2) at the garage door. The signals received by the antenna 100 are introduced to the coil 102 and are induced by that coil in the coil 104. The signals are then introduced to the control grid of the tube 112 to obtain an amplification of the signals in the stage which includes that tube.

The signals from the radio frequency (RF) stage are introduced through the transformer 122 to the detector stage which includes the diode 124. The detector stage operates to demodulate the signals by eliminating the carrier frequency. The output signals from the diode 124 represent the modulating signals at the low and high frequencies on a time-sharing basis. These signals are amplified by the stage including the tube 132 and by the stages including the tubes 142 and 150.

The amplified signals from the tube 150 are introduced to the tuned circuit formed by the coil 170 and the capacitance 172 and to the tuned circuit formed by the coil 174 and the capacitance 176. The circuit formed by the coil 170 and the capacitance 172 is tuned to the

low modulating frequency so as to pass signals only at that frequency. Similarly, the circuit formed by the coil 174 and the capacitance 176 is tuned to pass signals only at the high modulating frequency. In this way, the tuned circuits act to channelize the modulating signals of selected low and high frequencies into different channels.

The signals passed by the tuned circuits have amplitudes within relatively narrow limits because of the limiting action provided by the diodes 160 and 156. For example, signals having a positive amplitude above ground would pass through the diode 156 to ground such that they would be unable to be presented to the tuned circuits. Similarly, signals having a negative amplitude greater than -2 volts would be absorbed by the action of the diode 160 so as to be prevented from being introduced to the tuned circuits. The action of the diodes 156 and 160 in limiting the amplitudes of the signals introduced to the tuned circuit is important in obtaining the proper operation of subsequent stages, as will become more apparent subsequently. Actually, the diodes 156 and 160 are biased at a potential approximating -1 volt because of the flow of leakage current through the diodes. The diodes then act to limit any signal swing to an amplitude of 1 volt on either side of the bias of -1 volt.

The modulating signals passed by the coil 170 and the capacitance 172 are introduced through the coupling capacitance 180 to the control grid of the tube 184. These signals modulate the flow of current through a circuit including the power supply 123, the resistance 220, the coil 218, the resistance 188 and the tube 184. The resultant amplified alternating voltage produced on the plate of the tube 184 is fed back through the capacitance 192 to the cathode of the diode 196 for rectification by the diode. This positive rectified voltage is then smoothed and filtered by various members including the capacitance 204 and is then introduced from the resistance 198 to the control grid of the tube 184. In this way, the alternating signal introduced from the tuned circuit formed by the coil 170 and the capacitance 172 to the control grid of the tube 184 is converted into a direct voltage having a proportionate amplitude. As will be seen, the amplification of the alternating voltage and the production of an amplified direct voltage are accomplished in a single tube. This direct voltage causes a direct current to flow through the relay 218 and the resistance 220. The current flowing through the relay coil 218 has an amplitude within relatively narrow limits because of the limiting action provided by the resistance 188.

The tube 186 has a current flow through it upon a passage of signals through the tuned circuit formed by the coil 174 and the capacitance 176. The resonant signals produced on the plate of the tube 186 are introduced through the capacitance 194 to the cathode of the diode 206 to obtain a rectification of the signals. These rectified signals are then smoothed by the capacitance 214 so that a corresponding positive direct voltage is introduced to the control grid of the tube 186. In this way, a direct current flows through the relay coil 218 and the tube 186 upon the introduction of an alternating signal to the control grid of the tube. This current has an amplitude within relatively narrow limits because of the limiting action provided by the resistance 190.

The relay coil 218 is provided with parameters so that it can actuate the switch 224 only when current flows through both the tube 184 and the tube 186. In this way, the relay coil 218 can be operated only upon the reception at the receiver of modulating signals having the selected values at the low range and at the high range. The relay coil 218 can be actuated only upon the reception of modulating signals having the required low and high frequencies since each modulating signal is incapable of producing the required magnetic force in the relay coil 218 for actuating the switch 224. This results in part from the action of the diodes 156 and 160 and

also results in part from the action of the resistances 188 and 190.

The limiting action provided by the diodes 156 and 160 is instrumental in preventing any ringing action in the tuned circuit formed by the coil 170 and the capacitance 172 or in the tuned circuit formed by the coil 174 and the capacitance 176. If ringing were to occur in the tuned circuits, it would prolong the time of response of the circuits. This would tend to produce an actuation of the switch 224 by signals of intermittent pulse amplitude even though only one of the modulating frequencies should be received. In this way, the production of a ringing effect would tend to negate the advantages of using modulating signals concurrently at two different frequencies.

The resistances 188 and 190 also act to prevent the switch 224 from being actuated except when modulating signals at both selected frequencies are received. The resistances 188 and 190 act in this manner by limiting the flow of current through the relay 218 at any instant. By limiting the flow of current through the relay 218 at any instant, the relay is able to become energized sufficiently only on a cumulative basis to actuate the switch 224.

The capacitance 222 is included to provide a time delay for insuring that the switch 224 will become actuated only upon the continuous transmission of signals at the desired modulating frequencies from the transmitter and not as a result of any random varying generation of signals. The capacitance operates in this manner since it delays the build-up of any potential across the relay 218 for a particular period of time such as at least 1 second.

The apparatus disclosed above has certain important advantages. It is able to provide a discrimination between a multitude of different installations in a neighborhood even though the receivers at the different installations may all receive carrier signals at the same frequency. This results from the use of different combinations of modulating signals at low and high frequencies. For example, 44 different combinations of modulating patterns can be obtained when seven possible modulating frequencies are made available in the low range and nine possible modulating frequencies are made available in the high range. This may be seen from the chart shown in FIG. 7. Correspondingly increased numbers of combinations may be made available by increasing the number of choices in the low and high modulating ranges. By providing these different combinations, a clear-cut discrimination between different installations is obtained so that only the garage door at the desired installation becomes operated.

The apparatus constituting this invention has certain other important advantages. For example, the circuitry at the transmitter for producing the modulating signals at the low and high frequencies is relatively simple. This results from the production of the modulating signals at the two frequencies on a time-sharing basis. By producing the signals on a time-sharing basis, the same tuned circuit can be used to produce each frequency but additional reactance is inserted into the circuit periodically to change from one of the modulating frequencies to the other.

Additional advantages are also obtained from the particular construction of the transmitter. This results from the use of a single integral push button for obtaining the operation of the system constituting the invention. When depressed, this push button causes the radio receiver in an automobile to become shorted against the reception of any signals. At the same time, or preferably slightly thereafter, the depression of the switch causes power to be introduced to the stages for producing the carrier signals and the modulating signals. This sequence of operations prevents the radio receiver in the automobile from being damaged by any signals radiated by the antenna when signals are being transmitted toward the receiver at the garage door. It also prevents any reactance

from being introduced to the antenna 10 and the coil 11 from the input to the automobile radio so as to affect the operation of these members. It also prevents signals from being produced or from being radiated toward a garage door installation except during the time that the push button is positively actuated.

The circuitry at the transmitter is also advantageous to the operation of the receiver. This results from the fact that the signals at each of the two modulating frequencies are produced at the transmitter on a time-sharing basis and consequently are introduced to the receiver at separate times. This avoids the production of beat frequency signals and harmonics which would otherwise be produced if signals at the two modulating frequencies were introduced to the receiver at the same time. Since the signals at the two modulating frequencies are introduced to the receiver on a time-sharing basis, they can be easily and simply separated by the use of two resonant circuits tuned to the proper frequencies.

The receiver is also advantageous for another important reason. It provides a very convenient circuit for converting the alternating signals passing through the tuned circuits into a proportionate direct voltage. This direct voltage is amplified in the same circuit as that which receives the alternating voltage from the tuned circuits. The circuit is so constructed that a relay in the circuit can become sufficiently energized to actuate a switch only when modulating signals at the selected frequencies are able to pass through both of the tuned circuits. By converting in one stage the alternating signals into a proportionate direct voltage and using the direct voltage to control the operation of a relay, increased accuracies and sensitivities in the operation of the relay are obtained and without any increase in the number of required stages.

The apparatus constituting this invention has certain other important advantages. This results from the packaging of the transmitter shown in FIG. 1 and from the construction of the housing and the attachment of the housing to the dashboard of an automobile. As will be seen in FIG. 3, the transmitter is adapted to be attached to the dashboard 300 of an automobile at a position preferably under the dashboard and preferably directly beneath a radio 302 in the automobile.

The housing for the transmitter includes a first casing generally indicated at 304 in FIG. 4. The casing 304 is provided with a top wall 306, a pair of spaced side walls 308 and a rear wall 310. Pairs of holes 312 are provided in the top wall 306 at spaced positions in the longitudinal direction. The holes 312 in each pair are preferably disposed near the side walls 308 to provide a firm engagement between the casing 304 and the dashboard 300. This engagement is obtained by screws 314 which pass through any selected holes and into the dashboard 300.

A stud 318 extends downwardly from the top wall 306 of the casing 304 at a position intermediate the side walls 308 and toward the front of the casing. The stud 318 is internally threaded to receive a flat-headed screw 321 extending upwardly through a hole (not shown) in a casing generally indicated at 320. The casing 320 is provided with a bottom wall 322 and a front wall 324 (FIG. 5) to form an enclosed housing with the casing 304. The casing 320 is also reinforced by a pair of upwardly turned lateral flanges 325 (FIG. 4) which become disposed within the side walls 308 of the casing 304. The bottom wall 322 of the casing 320 is adapted to rest on a flange portion 326 extending horizontally inwardly from the rear wall 310 of the casing 304.

A name plate 328 is easily attachable to the front wall 324 of the casing 320 as by tabs (not shown). Since the name plate 328 is the member primarily visible to the riders in the automobile, it can be provided with the name of the manufacturer and can be provided with a pleasing appearance. A push button 330 (FIGS. 4 and

5) extends through holes in the front wall 324 and in the name plate 328. The push button 330 is coupled to the switches 14 and 16 in FIG. 1 to obtain a closure of the switches upon a depression of the push button and is spring-loaded as at 332 to maintain the switches in the normally opened position.

The casing 304 is initially attached to the dashboard 300 as by the screws 314. The casing 320 is thereafter attached to the casing 304 as by the flat-headed screw 321. Since the casing 320 carries all of the electrical components forming the transmitter shown in FIG. 1, the transmitter can be easily removed from the dashboard 300 for any desired adjustment or repair merely by removing the screw 321. A cable (not shown) leading to the radio (not shown) is included in the transmitter and is supported by the casing 320. The cable extends to the radio through an opening 334 in the rear wall 310 of the casing 304. Another cable also extends through the opening 334 to the antenna 10.

20 The apparatus described above is primarily adapted for use to provide a remote control over the operation of a garage door. It should be appreciated, however, that the apparatus constituting this invention is also adapted for other uses. For example, the transmitter can be disposed within a house and the receiver can be disposed in an automobile to obtain an automatic starting of the automobile a few minutes before the driver is ready to leave the house. In this way, the automobile engine can become fully warmed on winter days at the time that the driver is ready to leave.

25 The apparatus constituting this invention has been described primarily in connection with the production of modulating signals having low and high modulating frequencies. It should be appreciated that the modulations can be obtained in other ways than by differences in frequencies. For example, modulating signals having first and second characteristics can be produced by shifting the signals in phase to provide the signals with first and second distinctive phases.

30 It should be appreciated that semiconductors such as transistors can be used in place of the vacuum tubes shown in FIGS. 1 and 2 and described above. The reason for this is that both semiconductors and vacuum tubes serve as current control members.

35 Although this invention has been disclosed and illustrated with reference to particular applications, the principles involved are susceptible of numerous other applications which will be apparent to persons skilled in the art. The invention is, therefore, to be limited only as indicated by the scope of the appended claims.

40 1. In combination for controlling the operation of a garage door from a removed position in an automobile: an antenna connected in the automobile normally to receive radio signals for the reception of audio programs in the automobile; first switching means coupled to the antenna and operative to short circuit the input to the radio; second switching means coupled to the first switching means; 45 means coupled to the second switching means and operative upon the actuation of the switching means to produce carrier signals at a first particular frequency and including means coupled to the antenna for obtaining a transmission of the signals by the antenna; means coupled to the second switching means and operative upon the actuation of the switching means to produce modulating signals at a second particular frequency for modulating the carrier signals; means at the garage door for receiving the carrier signals; means coupled to the receiving means for demodulating the received signals to obtain only the modulating signals; and means coupled to the demodulating means for obtaining an operation of the garage door mechanism only upon the occurrence of modulating signals of the second particular frequency.

2. In combination for controlling the operation of a garage door from a removed position in an automobile: an antenna connected in the automobile normally to receive radio signals for the reception of audio programs in the automobile; means including a first tuned circuit for producing carrier signals and including a coil magnetically coupled to the antenna for introducing signals to the antenna for transmission to the garage door; means including a second tuned circuit for producing modulating signals at a particular frequency and coupled to the first tuned circuit for modulating the carrier signals; means including a first switch operative upon actuation to short circuit the input to the radio; means including a second switch ganged to the first switch and operative upon actuation to introduce a potential to the first and second tuned circuits for obtaining the production of the carrier and modulating signals; means at the garage door for receiving the transmitted signals; means coupled to the receiving means for demodulating the received signals; and means coupled to the demodulating means and responsive to modulating signals at the particular frequency for obtaining an operation of the garage door.

3. In combination for controlling the operation of a garage door from a removed position in an automobile: an antenna connected in the automobile normally to receive radio signals for the reception of audio programs in the automobile; means including a first tuned circuit for producing carrier signals and including a coil magnetically coupled to the antenna for introducing signals to the antenna for transmission to the garage door; a second tuned circuit resonant at a first particular modulating frequency and coupled to the first tuned circuit for providing a modulation of the carrier signals; means including reactance means disposed electrically for coupling to the tuned circuit and adjustable to produce a resonance in the circuit at a second particular modulating frequency; means including a first switch operative upon actuation to short circuit the input to the radio; means including a second switch ganged to the first switch and operative upon actuation to introduce a potential to the first and second tuned circuits for obtaining the production of carrier and modulating signals; means coupled to the second switch and operative upon actuation of the second switch to alternately obtain a coupling of the reactance means to the second tuned circuit and a decoupling of the reactance means from the circuit to alternately obtain the production of signals at the first and second modulating frequencies; means at the garage door for receiving the transmitted signals; means operative upon the received signals for detecting the received signals to pass only the modulating signals; means coupled to the detecting means and including a first circuit resonant to pass modulating signals only of the first particular frequency and including a second circuit resonant to pass modulating signals only of the second particular frequency; and means responsive only to modulating signals of both the first and second particular frequencies to obtain operation of the garage door.

4. The combination set forth in claim 3, in which the door-operating means includes a pair of stages each coupled to a different one of the resonant circuits to receive modulating signals of a different one of the two selected frequencies and each constructed to amplify the modulating signals and including unidirectional means to convert the amplified alternating signals into a proportionate direct current and in which the door-operating means includes means coupled to the last-mentioned stages for operation only upon the concurrent flow of a direct current through both of the stages.

5. In combination for controlling the operation of a distant mechanism from a removed position: a tuned circuit resonant at a first particular modulating frequency; reactance means electrically disposed to become coupled to the tuned circuit upon the establishment of particular connections between the reactance means and the tuned

circuit to obtain resonance of the tuned circuit at a second modulating frequency; an antenna for receiving signals; switching means coupled to the antenna for inhibiting the reception of signals by the antenna upon the operation of the switching means; means operatively coupled to the reactance means and the tuned circuit and to the switching means for establishing the connections between the reactance means and the tuned circuit and for disestablishing such connections on a time-sharing basis upon the operation of the switching means to produce modulating signals alternately at the first frequency and at the second frequency; means operatively coupled to the antenna and the last mentioned means for providing carrier signals at a third selected frequency and for modulating the carrier signals with the signals alternately produced at the first and second frequencies to produce signals for transmission to the distant mechanism and for introducing such modulated signals to the antenna for transmission by the antenna to the removed position; means at the distant mechanism for receiving the transmitted signals; means coupled to the receiving means for separately demodulating the received signals to introduce modulating signals only at the first frequency to a first channel and to introduce modulating signals only at the second frequency to a second channel; and means coupled to the demodulating means and responsive only to the modulating signals of both the first and second frequencies on the time-sharing basis for producing an output signal for operating the distant mechanism.

6. In combination for controlling the operation of a distant mechanism from a removed position by obtaining the transmission of signals from an antenna normally adapted to receive radio signals; first switching means operatively coupled to the antenna to prevent the reception of the radio signals by the antenna upon the actuation of the first switching means; means operatively coupled to the antenna and responsive to the actuation of the first switching means for providing carrier signals at a selected frequency and for introducing such signals to the antenna for transmission by the antenna; means including tuned electrical circuitry and including second switching means responsive to the actuation of the first switching means for alternately varying the characteristics of the tuned electrical circuitry to modulate the carrier signals with signals of a first selected frequency at first particular periods of time and for modulating the carrier signals with signals of a second selected frequency different from the first frequency at second particular periods alternating with the first particular periods; means responsive to the modulated carrier signals for transmitting the modulated carrier signals toward the distant mechanism; means at the distant mechanism for receiving the transmitted signals; detecting means operative upon the received signals to pass only the modulating signals; means including tuned electrical circuitry responsive to the modulating signals for separately passing the first modulating signals of the first selected frequency and the second modulating signals of the second selected frequency; means including first detecting means responsive to the first modulating signals to produce a first detected signal and including second detecting means responsive to the second modulating signals to produce a second detected signal and including means coupled to the first and second detecting means for producing an output signal only upon the sequential production of the first and second detected signals; and means responsive to the output signals for obtaining an operation of the distant mechanism.

7. In combination for controlling the operation of a distant mechanism from a removed position by obtaining the transmission of signals to the removed position by an antenna normally adapted to receive radio signals: a capacitance; means including a first tuned circuit and first switching means for alternately coupling the capacitance into the circuit and isolating the capacitance from the

circuit upon alternate operations of the first switching means to produce modulating signals having first and second particular frequencies on a particular time-sharing basis; means including a second tuned circuit for providing carrier signals and coupled to the first tuned circuit and to the antenna for modulation of the carrier signals by the modulating signals having the first and second particular frequencies and for transmission of the modulated carrier signals by the antenna to the distant mechanism; second switching means operatively coupled to the antenna for preventing the reception of signals by the antenna upon the actuation of the second switching means and operatively coupled to the first switching means for obtaining the alternate operation of the first switching means upon the actuation of the second switching means; receiving means at the distant mechanism; detecting means coupled to the receiving means for extracting the modulating signals; first means coupled to the detecting means and resonant at the first modulating frequency for passing only the first modulating signals; second means coupled to the detecting means and resonant at the second modulating frequency for passing only the second modulating signals; first detecting means coupled to the first resonant means for converting the first modulating signals into a first direct voltage related to the amplitude of the signals; second detecting means coupled to the second resonant means for converting the second modulating signals into a second direct voltage related to the amplitude of the signals; means coupled to the first and second detecting means and responsive only to the cumulative effect of the first and second direct voltages for producing an output signal; and means responsive to the output signal for obtaining an operation of the distant mechanism.

8. In combination for controlling the operation of a distant mechanism from a removed position by obtaining the transmission of signals to the removed position by an antenna normally adapted to receive radio signals: a tuned circuit resonant at a first particular frequency; switching means operatively coupled to the antenna for preventing the reception of signals by the antenna upon the actuation of the switching means; resonant means including a capacitance disposed electrically for coupling to the tuned circuit and adjustable to produce a resonance in the circuit at a second particular frequency; second switching means operative at a particular repetition rate and responsive to the actuation of the first switching means to connect the capacitance into the tuned circuit and to disconnect the capacitance from the circuit on a time-sharing basis related to the particular repetition rate; means for providing carrier signals at a third particular frequency and operatively coupled to the resonant means for obtaining a modulation of the carrier signals with the signals at the first and second frequencies and operatively coupled to the antenna for obtaining a transmission of the modulated carrier signals by the antenna to the distant mechanism upon the actuation of the switching means; means at the distant mechanism for receiving the transmitted signals; means coupled to the receiving means for demodulating the received signals to produce modulating signals alternately at the first frequency and at the second frequency; and means coupled to the demodulating means for producing an operation of the distant mechanism only upon the alternate passage of modulating signals at the first and second frequencies through the demodulating means at the particular repetition rate.

9. In combination for controlling the operation of a garage door from a removed position in an automobile and for simultaneously preventing the reception of radio signals by an antenna on the automobile: means operatively coupled to the antenna for providing carrier signals at a selected frequency and for introducing the carrier signals to the antenna for transmission by the antenna toward the garage door; switching means operatively coupled to the antenna for preventing the reception of signals by the antenna upon the actuation of the switch-

ing means; means operative upon the carrier signals and responsive to the actuation of the switching means for modulating the carrier signals with alternating signals of a particular frequency; means at the garage door for receiving the modulated carrier signals; means responsive to the modulated carrier signals for detecting the modulated carrier signals to pass only the modulating signals; a stage responsive to the modulating signals from the detecting means and including a current control member for amplifying the signals and including unidirectional means for rectifying the signals from the current control member and including a capacitance for smoothing the rectified voltage into a direct voltage and including impedance means for feeding the direct voltage to the current control member for further amplification by the current control member of the direct voltage; and means including a relay responsive to the flow of direct current through the current control member to obtain the operation of the garage door.

10. In combination for controlling the operation of a garage door from a removed position in an automobile and for simultaneously preventing the reception of signals by an antenna on the automobile: switching means operatively coupled to the antenna for preventing the reception of signals by the antenna upon the actuation of the switching means; means including electrical circuitry responsive to the actuation of the switching means for providing modulating signals of a selected low frequency and modulating signals of a selected high frequency on a time-sharing basis; means including electrical circuitry operatively coupled to the antenna and the last mentioned means for providing carrier signals of a third selected frequency and for modulating the carrier signals with the modulating signals of the selected low and high modulating frequencies and for introducing the modulated signals to the antenna for transmission by the antenna toward the garage door; means including electrical circuitry at the garage door for receiving the transmitted signals; means including electrical circuitry coupled to the receiving means for detecting the received signals; means including first resonant circuitry responsive to the modulating signals of the selected low frequency and including second resonant circuitry responsive to the modulating signals of the selected high frequency for separately passing the signals of the selected frequencies; a first electrical stage responsive to the modulating signals of the selected high modulating frequency from the resonant means and including first current control means for amplifying the signals and including first unidirectional means for rectifying the amplified signals from the current control means and including a first capacitance for smoothing the rectified voltage from the unidirectional means into a direct voltage and including first impedance means for introducing the direct voltage from the first capacitance to the current control means for amplification of the direct voltage; a second electrical stage responsive to the modulating signals of the selected low modulating frequency from the resonant means and including second current control means for amplifying the signals and including second unidirectional means for rectifying the amplified signals from the second current control means and including a second capacitance for smoothing the rectified voltage from the unidirectional voltage into a direct voltage and including second impedance means for introducing the direct voltage from the second capacitance to the current control means for amplification of the direct voltage; means including a relay responsive to the current through the first and second current control means to become energized only upon a concurrent flow of current through these means; and means responsive to the relay when energized to obtain an operation of the garage door.

11. In combination for controlling the operation of a garage door from a removed position in an automobile and for preventing the reception of signals by an antenna on the automobile: switching means operatively coupled

to the antenna for preventing the reception of signals by the antenna upon an actuation of the switching means; means including a tuned coil and a first capacitance connected across the coil for providing modulating signals having a selected high frequency; means including a second capacitance electrically connected to become coupled to the tuned coil and the first capacitance for providing modulating signals having a selected low frequency; means including a vibrator operatively coupled to the switching means for producing an alternate coupling of the second capacitance to the first capacitance and the tuned coil and an alternate de-coupling of the second capacitance from the tuned coil and the first capacitance upon an actuation of the switching means; means including a tuned circuit for producing carrier signals and for modulating the signals with the modulating signals of low and high frequencies and for introducing the modulated signals to the antenna for transmission by the antenna toward the garage door; means at the garage door for receiving the transmitted signals; means coupled to the receiving means for detecting the received signals to pass only the modulating signals; means responsive to the signals from the detecting means and including a first resonant circuit for passing only the modulating signals of the selected high frequency and including a second resonant circuit for passing only the modulating signals of the selected low frequency; circuit means coupled to the detecting means for limiting the amplitudes of the modulating signals passing to the first and second resonant means to prevent any ringing in the resonant means; and means coupled to the first and second resonant means and responsive only upon the concurrent introduction of the modulating signals of the selected low and high frequencies to provide an operation of the garage door.

12. The combination set forth in claim 11, in which: the door-operating means includes a first stage for receiving the modulating signals of limited amplitude and of the selected low frequency and in which the first stage includes a first current control member for amplifying these signals and in which the first stage includes first means for rectifying and smoothing the amplified modulating signals from the first current control member into a direct voltage and in which the first stage also includes

5 first means for introducing the direct voltage from the first rectifying and smoothing means to the first current control member and in which the first stage includes first means for limiting the current through the first current control member; and in which the door-operating means includes a second stage for receiving the modulating signals of limited amplitude and of the selected high frequency and in which the second stage includes a second current control member for amplifying these signals and in which the second stage includes second means for rectifying and smoothing the amplified modulating signals from the second current control member into a direct voltage and in which the second stage also includes second means for introducing the direct voltage from the second rectifying and smoothing means to the second current control member and in which the second stage includes second means for limiting the current through the second current control member; and in which the door-operating means includes a relay coupled to the current-limiting means in the first and second stages to become energized only upon the concurrent flow of current through these limiting means, and in which the door-operating means also includes a switch actuated by the relay.
